[57] CLAIM

The ornamental design for an African American headpiece, as shown and described herein.

DESCRIPTION

FIG. 1 is a front perspective view of an African American headpiece showing my new design; FIG. 2 is a top plan view thereof; FIG. 3 is a front elevational view thereof; FIG. 4 is a rear elevational view thereof; FIG. 5 is a right side elevational view thereof; FIG. 6 is a left side elevational view thereof; FIG. 7 is a bottom plan view thereof; FIG. 8 is a perspective environmental view of a headpiece, showing my new design in full lines and the environmental matter in broken lines for illustrative purposes only and forming no part of the claimed design; FIG. 9 is a second perspective environmental view of a headpiece, showing my new design in full lines and the environmental matter in broken lines for illustrative purposes only and forming no part of the claimed design; and, FIG. 10 is a third perspective environmental view of a headpiece, showing my new design in full lines and the environmental matter in broken lines for illustrative purposes only and forming no part of the claimed design.
